PROJECTOR FOR PAGE PRINTERS

Reginald G. Schuler, Highland Park, Ill., assignor to Teletype Corporation, Chicago, Ill., a corporation of Delaware

Original application July 17, 1940, Serial No. 346,003. Divided and this application September 18, 1941, Serial No. 411,373

9 Claims. (Cl. 197—125)

1

The present invention pertains to printing telegraph apparatus and more particularly to page printers having movable platens.

This application is a division of application Serial No. 346,003, filed July 17, 1940.

The primary object of the invention is to provide a page printer having means for automatically distributing the wear of the platen due to the printing impact thereon.

Features of the invention reside in providing a disc platen movable with the type carriage wherein printing is effected on the periphery of the disc and the number of hidden printed characters is reduced to a minimum; and means for assuring even wear of the platen by automatically changing its printing point, haphazardly or in a random manner.

The foregoing and other objects and features of the invention will appear from the following detailed description taken in conjunction with the accompanying drawings, in which,

Fig. 1 is an enlarged side view and partial section of the printer mechanism according to the present invention with part of the optical arrangement with which the printer is associated;

Fig. 2 is an enlarged cross-sectional view of the printer platen and platen frame;

Fig. 3 is a view taken substantially on line 3—3 of Fig. 2;

Fig. 4 is a top view of the part of the printer mechanism shown in Figs. 2 and 3; and

Fig. 5 is an enlarged side view of a type bar head.

Having reference to Fig. 1 a page printer of the type shown in U. S. Patent 1,904,164 is shown. The printer indicated generally as 16 (and parts of which only have been shown) has been modified in certain respects to adapt it for use with the projector of the present invention. The page printer comprises the side frames 18 and 19 to which is pivoted at 81 a platen frame indicated generally as 82. The usual cylindrical form of platen has been dispensed with in the present embodiment of the invention and has been substituted by the disc form of platen 173 which will be hereinafter described.

To provide a running account of the message printed on the page material a delivery mechanism is provided which comprises a means for permitting the record material to escape from the supply roll, suitable guides, and a web pulling means whereby the page material is advanced through the printing zone. The page material 49 in being withdrawn from the roll 83 is directed over a slack bar 84 which is pivoted at 85 and is

2

normally biased clockwise by a spring 86 to maintain the page material or Cellophane web taut between the roll 83 and a cylindrical guide 87 carried on a shaft 88 journaled in plates 89 depending from side frames 18 and 19. The web 49 is then directed over a roller 91 to which is fixed a ratchet wheel 92, the ratchet wheel and roller being carried on a shaft 93 journaled in the plates 89 secured to side frames 18 and 19. Cooperating with the roller 91 is a pressure roller 94 which is carried on a standard 96 secured to a rock shaft 97. Pressure roller 94 is drawn into pressing relation with roller 91 by means of a spring 98. Secured to rock shaft 97 and located in juxtaposition to plate 89 is a pressure roller release lever 99. Cooperating with lever 99 is a shoulder 101 on plate 89 arranged so that when lever 99 is actuated counterclockwise against the action of spring 98 it will latch up behind or on the left-hand side of the shoulder 101 thereby releasing the pressure roller 94 from engagement with pressure roller 91 and maintaining this condition, until lever 99 is again released from the shoulder 101 to permit spring 98 to bring roller 94 again into pressing relation with roller 91. Associated with the ratchet wheel 92 is a pawl member 102 which is pivoted to a bell crank lever 103 carried on a pivot shaft 104. The depending arm of bell crank lever 103 is pivoted to one end 30 of a push rod 106, the other end of which is shouldered to cooperate with a function bail 108 in the manner shown in the afore-mentioned Patent 1,904,164. Thus in response to a predetermined selection a function lever, similar to function lever 107 (shown in Fig. 1) is selected to raise the free end of push bar 106 upwardly into the path of the function bail blade 108. Then, when the push rod 106 is actuated leftwardly by the function bail 108, clockwise rotation is imparted to bell crank lever 103 to impart in turn, downward movement to pawl 102. In this manner, the ratchet wheel 92 is rotated clockwise one step, which through the cooperation of pressure rollers 91 and 94, acts in cooperation with a web pulling device to deliver a predetermined amount of record material 49 from the supply roll 83 to the printing zone and the projection area.

The record material 49 is brought to the printing position by means of a pulling or drawing mechanism now to be described. The record material 49 as it leaves roller 91 is directed around guide rods 109, 111 and 112. These guide rods may take the form of a fixed rod carrying guide 50 rollers thereon to eliminate friction. From the

guide rod 112 the record material 49 is directed vertically through the printing zone and projection field to a guide rod 113 carried by a U-shaped shifting frame member 114 pivotally carried on pivots 115 suitably journaled in the frame indicated generally as 15, which supports the printer apparatus. The page material 49 is then directed around a guide rod 117 carried in supports 118 depending from bars 119 secured to angle iron cross bars 121 and 122 of frame 15. From thence, the page material 49 is directed around a spindle 123 fixed to a shaft 124 journaled in standards 126 supported on said bars 119.

Shaft 124 is interconnected through a friction clutch to a pulley 128. Continuous counterclockwise rotation (as viewed in Fig. 1) is imparted to pulley 128 through the instrumentality of a belt 129 connected to a pulley 131 fixed to the main operating shaft 132 of the page printing apparatus shown in Patent 1,904,164. Shaft 132 carries a gear (not shown) which meshes with a pinion gear fixed to the shaft of a motor (not shown). The motor, therefore, imparts continuous rotation to pulley 128 which through the friction clutch imparts a constant torque through shaft 124 to spindle 123. With this arrangement the page material 49 is maintained in a taut condition between the spindle 123 and the roller 91. Thus, when the ratchet 92 is rotated one step, a predetermined amount of the page material 49 is delivered from the supply roller 83, which material is immediately taken up by the spindle 123 to preserve the taut condition of the page material. As disclosed in the afore-mentioned Patent 1,904,164, the page printer 16 is controlled telegraphically by a selector magnet 137. This is connected in a signal line (not shown) on which are impressed code combinations of signalling impulses. The code signals control, through a selector magnet 137 of a sword and T-type selector (not here shown, but illustrated and described in said patent), a series of selector vanes 138 which in turn controls through a series of bell cranks (as shown in said patent) a set of curved code bars 141. Code bars 141 and said bell cranks are supported on a movable type carriage, indicated generally by the numeral 142, which is provided with rollers 143 and 144 whereby it is adapted to travel on tracks 145 and 146, respectively, positioned between side frames 78 and 79. Cooperating with code bars 141 are a plurality of pull bars 147 having individual springs 148. Pull bars 147 are operatively connected by rack and pinion connections to a corresponding plurality of type bars 149 pivoted on a shaft 151.

Type carriage 142 is also provided with a spacing rack 152 which cooperates with a spacing mechanism (not shown) similar to that illustrated in Patent 1,904,164, to control the movement of type carriage 142 to form character spaces, tending in this movement to wind up a carriage return spring mechanism (not shown). Upon receipt of the carriage return signal, a function lever (similar to lever 107) is selected and the carriage return mechanism actuated in the manner described in the afore-mentioned Patent 1,904,164. A pull bar ball 153 is mounted in the type carriage 142 and is provided with a roller 154 carried on the bottom side thereof on a stud 155. Roller 154 operates between a pair of blades 156 and 157 of a main printing bail 158 so that bail 153 can be reciprocated by bail 158 in any character spacing position of the type carriage 142. Fastened to the printing bail 158 is one end of a printing spring 159, the other end of which

is connected to a printing blow adjustment means as shown in Patent 1,904,164. Bail 158 is mounted on a shaft 161 on which is also carried a printing bail actuator 162 which cooperates with a printing cam 163. Actuator 162 carries at the end of its upper arm a stud 164 which has abutting relation only with printing bail 158 and is not permanently connected thereto, which is to permit spring printing. Printing bail 158 is also provided with a pair of arms 166 which carry a function lever bail 169. Also carried on shaft 161 is a function bail comprising arms 165 and 167. Arm 165 is provided with a follower roller which cooperates with a function bail cam 168, and arm 167 supports on its end the function bail blade 108.

Associated with the selector vanes 138 are a plurality of function levers 107 mounted on pivot rod 171 and provided with individual springs 172 which tend to rotate the function levers clockwise into registry with the selector vanes 138. The function levers 107 are normally held out of engagement with the selector vanes 138 by means of the rod 169 of the function lever bail.

As previously mentioned, the platen frame 82 is pivotally supported on pivots 81 in side frames 78 and 79. The platen comprises a circular disc 173 (Figs. 1, 2, 3, and 4) rotatably mounted on a carriage 174 which is slidable on rods 175 and 176 carried by platen frame 82. Platen carriage 174 is connected to the type carriage, as will be presently described, so as to be movable therewith, the effective printing edge of the platen 173 being located coincident with the printing point or zone determined by the path of operation of the type bar 149.

The platen frame 82 is adapted to be rocked from the "letters" or unshift position to the "figures" or shift position in the manner fully set forth in the afore-mentioned Patent 1,904,164. Briefly, the side frame of the platen frame 82 (as shown in Figs. 1 and 2) is provided with a lug 177 which operates between two adjustable stops 178 and 179. Adjacent to lug 177 there is pivoted to the side frame of the platen frame 82 on pivot 181, the upper end of a link 182, the lower end of which is pivoted to the horizontal arm of a bell crank lever 183 pivotally mounted at 184. To the lower end of the depending arm of bell crank 183 is pivoted a push bar 185, the free end of which overlies a leftwardly directed arm of the function lever 107. Push bar 185 is also provided with a shoulder 186 which cooperates with the function bail blade 108. The platen frame 82 and platen 173 are shown in Figs. 1 and 2 in the "letters" or unshift position, with the stop lug 177 against the upper stop screw 178. This condition is achieved when the function bail blade 108 has operated upon the shoulder 186 to move the push bar 185 leftwardly to rotate the bell crank 183 clockwise, thus raising the link 182 to cause the platen frame 82 to rock clockwise.

A correspondingly similar construction is provided for the "figures" or shift mechanism. That is a shift function lever similar to lever 107 is provided which when selected is caused to rotate clockwise to bring its rearwardly extending arm into operation to raise a push bar, similar to bar 185, into the path of the function bail blade 108 which, when it is permitted to operate leftwardly (as viewed in Fig. 1) will cause a bell crank lever similar to bell crank lever 183, to pull down a link similar to 182 to rock the platen frame 82 counterclockwise to bring its stop 177 against the lower stop screw 179. The platen frame 82 is main-

tained in its shift or unshift position by a spring actuated detent member 187 acting on a detent roller 188.

In Figs. 2, 3, and 4 is illustrated the manner in which the platen carriage 174 is connected to the type carriage 142 so as to be movable therewith. As previously mentioned, the platen carriage 174 is slidably supported on rods 175 and 176. Carriage 174 is provided with an eccentric stud engaged by the forked end of a bar 189, the left end of which (as viewed in Fig. 3) is secured to a member 191 which is secured by screws 192 to the type carriage 142. As viewed in Fig. 4, the circular platen 173 is rotatably mounted on the platen carriage 174 by means of an eccentric means 193. By means of the adjustment 193 the platen 173 is adjustable toward and away from the record material to vary the clearance therebetween. Rightward and leftward adjustment as viewed in Figs. 9 and 10, is also provided for the platen 173, through the instrumentality of the eccentric adjusting means 190.

An important feature of the present invention is the provision of a platen so positioned as to reduce to a minimum the obstruction of the projected image by the platen. To achieve this result the platen 173 is tilted with respect to the record material printed upon, sufficiently to clear the light cone. The peripheral surface of the platen 173, upon which printing is effected is slightly beveled so that in one of the shift positions of the platen the peripheral surface of the platen will be parallel to the record material. In the present embodiment the peripheral surface of the platen 173 is parallel to the record strip when the platen frame 82 has been shifted to the upper case position as indicated in Fig. 2 by the dotted line 194 of the platen 173.

To compensate for this arrangement of the platen 173, the type faces on the type bar 149 are arranged as shown in Fig. 5. Moreover, this arrangement of type faces in cooperation with a shield 195 (Fig. 2) serves (as will presently appear) to prevent smudging during the printing operation. As is well known, the type bar 149 is provided with an upper case type face 196 and a lower case type face 197 (Fig. 5). However, according to the present invention the lower case type face 197 is provided with a slope corresponding to the slope of the periphery of the platen 173 when in the lower case position. The dimension 201 of the upper case type 196 is arranged to be slightly less lower than the minimum height 210 of the lower case type 197. When printing is effected in the lower case position, the type face 196 being lower than the type face 197, will not touch the record material and hence no smudging of the printed record will occur.

When printing is effected in the upper case position, means is provided for preventing the lower case type face 197 from coming into direct contact with the surface of the record material. To achieve this result a shield 195 is provided which is adapted to be interposed between the type face 197 and the platen 173 when printing is being effected in the upper case position. Shield 195 is secured to the ribbon oscillating member 199, which, as described in the aforementioned Patent 1,904,164 oscillates the inking ribbon into and out of the path of the type faces during the printing operation. The ribbon oscillator 199 is pivotally articulated to arm 201 of a lever 202 which in turn is pivoted at 203 to a lever 204 pivoted at 220 to the type carriage 142. Lever 204 is arranged to carry a roller 205

which rides on the bottom side of a rail 206 mounted on the platen frame 82, as disclosed in the afore-mentioned Patent 1,904,164. Roller 205 is pressed against the rail 206 by a spring (not shown), so that when the platen frame 82 is rocked between the shift and unshift positions, roller 205 will constantly contact with said rail 205, and lever 202 will be reciprocated therewith.

The depending arm 208 of the lever 202 is operably associated with the pull-bar bail 153 (Fig. 1) so that the reciprocative motion of bail 153 will cause the oscillation of the lever 202 about pivot 203, whether the platen frame 82 is in the shift or the unshift position. Thus when the bail 153 is in its normal position (the leftward position as shown in Fig. 1), the lever 202 will hold the inking ribbon, through the instrumentality of the ribbon guide (not shown) located at the upper extremity of member 199 (Fig. 2), in its downward position to effect visibility of the printed character. When the bail 153 moves rightwardly for a printing operation, the ribbon will be raised to printing position due to the counterclockwise movement imparted to the lever 202 by the bail 153. When the platen frame 82 is in the position shown in Fig. 2 which is the lower case printing position, the shield 195, upon oscillation of lever 202, will not be raised sufficiently to be interposed between the type face 197 and the platen 173. However, when the platen frame 82 is in the upper case printing position with the platen 173 in printing relation with the upper case type face 196, the shield 195 will, upon reciprocation, be raised so as to become interposed between the lower case type face 197 and the record material, thus preventing any ink which has accumulated on the type face 197 from smudging the record material.

As illustrated in Figs. 2, 3, and 4 there is provided a platen rotator for automatically changing the printing point of the platen 173 in response to each carriage return operation. As previously described, the platen 173 spaces with the type carriage 142, and accordingly is spaced step-by-step for character spacing and, upon reaching the end of the line, the platen 173 is returned rapidly with the carriage 142 to the beginning-of-line position. In contact with the platen 173 at a point opposite to the printing point is a closely wound coiled spring 200 which is connected at its ends to the side frame members of the platen supporting frame 82, in such manner that the platen 173 is caused to rotate as it advances during character spacing. Moreover, upon the rapid return movement of the platen 173 (under the influence of the carriage return spring 150) during the performance of the carriage return function, the platen 173 will, owing to the combined sliding and rolling relation with the yieldable spring member 200, rotate haphazardly, thus causing the same printing point of the platen to be presented to the type bars a minimum number of times. In other words, through the instrumentality of the platen rotator 200, the platen 173 is controlled in such manner as to reduce to a minimum the number of times any particular printing point on the platen is impinged upon, thereby reducing to a minimum the wear at any given point and hence prolonging the life of the platen. In lieu of the coiled spring 200, a taut wire or cord can, of course, be used.

It is, of course, manifest that the features herein disclosed may be modified without de-

parting from the spirit and scope of the present invention, which is intended to be limited only as set forth in the appended claims.

What is claimed is:

1. In a printing apparatus, a printing bail, a plurality of type bars, means for supporting said type bars, said means slidably articulated to said printing bail, a platen cooperably related to said type bars, means for shifting said platen between two positions indicative of upper and lower case, means for rendering said platen movable with said type bar supporting means independently of the operation of the platen shifting means, and means effective under certain operating conditions to change the rotational position of said platen haphazardly irrespective of the shift position of said platen.

2. In a recorder, a carriage movable to form character spaces, means for advancing said carriage, a platen rotatably mounted on said carriage, carriage return means, and means effective upon each operation of said carriage by said return means to change the rotational position of said platen haphazardly.

3. In a printing apparatus, a printing bail, a movable type carriage slidably articulated to said printing bail, a platen rotatably carried by said carriage and movable therewith, and means effective upon each movement of said carriage to rotate said platen haphazardly.

4. In a printing apparatus, a printing bail, a plurality of type bars, means for supporting said type bars, said means slidably articulated to said printing bail, a platen cooperably related to said type bars, means for rendering said platen movable with said type bar supporting means, and means effective upon each movement of said type bar supporting means to rotate said platen haphazardly.

10

15

20

25

30

35

5. In a printing apparatus, a printing bail, a movable type carriage slidably articulated to said printing bail, a platen rotatably carried by said carriage and movable therewith, and resilient means effective upon each movement of said carriage to rotate said platen.

6. In a printing apparatus, a printing bail, a movable type carriage slidably articulated to said printing bail, a platen rotatably carried by said carriage and movable therewith, and a taut wire means effective upon each movement of said carriage to shift said platen angularly.

7. In a printing apparatus, a printing bail, a movable type carriage slidably articulated to said printing bail, a platen rotatably carried by said carriage and movable therewith, a taut wire instrumentality, and means in said carriage effective in cooperation with said instrumentality upon each movement of said carriage to shift said platen angularly.

8. In a printing apparatus, a printing bail, a movable type carriage slidably articulated to said printing bail, a platen rotatably carried by said carriage and movable therewith, and a coiled spring instrumentality effective upon each movement of said carriage to rotate said platen.

9. In a printing apparatus, a printing bail, a movable type carriage slidably articulated to said printing bail, a platen rotatably carried by said carriage and movable therewith, said platen having a portion of its peripheral surface provided with a circumferential groove, and a coiled spring instrumentality cooperating with said groove, whereby, upon each movement of said carriage, said instrumentality is effective to rotate said platen.

REGINALD G. SCHULER.
